Attorney.

UNITED STATES PATENT OFFICE.

BÉLA KREITH, OF BUDAPEST, AUSTRIA-HUNGARY.

COMBINED FIREARM AND BOXER.

1,023,741.

Specification of Letters Patent.

Patented Apr. 16, 1912.

Application filed February 11, 1909. Serial No. 477,433.

To all whom it may concern:

Be it known that I, BÉLA KREITH, count, a subject of the King of Hungary, residing at Budapest, in the Kingdom of Hungary, have invented new and useful Improvements 5 in Combined Firearms and Boxers; and I do hereby declare the following to be a full, clear, and exact description of the same.

My invention relates to a combined fire 10 arm and knuckle duster and will be described more fully with reference to the annexed drawing, which shows as an example two embodiments of my invention applied on a pistol.

Figure 1 shows one form in side elevation, Fig. 2 another form ready for thrusting.

1 is the knuckle duster shaped in a manner to be fitted to the stock 2 of the pistol. The knuckle duster has for this purpose an 20 extension 3 engaging the bottom part 4 of the stock, while the front end 5 of the knuckle duster is adapted to engage the guard 6. Suitable means are provided for securing the knuckle duster on the pistol. 25 In the drawing a screw 7 is shown engaging a screwthreaded boring of the guard 6. However any other means for instance clamps may be used instead of the screw.

At the bottom part of the knuckle duster 30 a thrust blade 8 may be arranged pivotally on a pivot 9 parallel with or perpendicular to the plane of the blade. When the thrust blade is not used it fits closely the side face of the stock or may also enter a recess 35 of the side face of the latter, so that the blade does not project from the surface of the stock.

The dotted lines show the position of the fingers of the hand when the pistol is used. 40 The fore finger 10 rests on trigger 11 within the guard, while the other fingers 12 are passed through the opening 13 formed between the knuckle duster and the stock of the pistol.

45 In Fig. 1 the knuckle duster is shown as an attachment applicable to pistols, however the knuckle duster may be manufactured in one piece with the pistol as shown in Fig. 2. In this latter embodiment instead of the one opening 13, every one of the fingers 12 has a separate opening 14, 15 and 16. In Fig. 2 the blade 8 is shown in its position ready for use.

50 The forms shown in the drawing are only examples and the construction may be varied in different manners without depart-

ing from my invention. Thus for instance the knuckle duster may or may not be fitted with the thrust blade. Further there can be provided a spring snap to secure the 60 blade in its rest or working position.

My invention can be applied on every kind of hand fire arm with short barrel viz. revolvers, repeating pistols such as the well known Browning pistols, etc.

65

The combined knuckle duster and pistol is a complete arm for defense the advantages of which are the following: 1. The knuckle duster serves for defense when the cartridges are exhausted or if the pistol missed 70 fire. 2. The knuckle duster protects the hand and may be used to ward sword blows. 3. The knuckle duster insures a strong grip so that the arm cannot be easily wrenching 75 from one's hand. 4. The blade 8 enables the 75 arm to be used as a thrust arm if the necessity occurs therefor.

Having described my invention, what I claim is:

1. In a device of the class described, the 80 combination of a pistol butt; a knuckle duster secured thereto and adapted for protection and passage of the fingers, the upper part of the duster forming a trigger guard; and a thrust blade pivoted to the lower part 85 of the duster and adapted to be extended or to be folded against the side of the butt, in which position it may be held by the fingers and thumb holding the butt.

2. In a device of the class described, the 90 combination of a pistol butt; a detachable knuckle duster secured thereto and adapted for the protection and passage of the fingers in front of the butt, the upper part of the 95 butt forming a trigger guard and the lower end of the duster being extended rearwardly and engaging under and secured to the butt and provided with a recess; a pivot pin passing through said recess substantially perpendicular to the butt; and a thrust-

100

blade pivotally mounted on said pin perpendicular thereto and adapted to be moved in alinement with the butt or against and parallel to the side thereof, in which position it may be held in place by the thumb and finger grasping the butt.

105

3. In a device of the character described, the combination of a pistol butt; a detachable knuckle-duster secured thereto and provided with a series of openings, one for each 110 finger, and with a rearward extension engaging under the butt and provided with

a recess, the uppermost of said openings being horizontally elongated and forming the trigger guard; a pivot pin passing through said recess substantially perpendicular to the axis of the butt; and a thrust-blade pivotally mounted at its inner end on said pin perpendicular thereto and adapted to be moved in substantial alinement therewith, said blade being also adapted to be pivotally moved parallel to and flat against the side of the butt, in which position it may be held in place by the thumb and the ends of the fingers grasping the butt and duster.

4. In a device of the class described, the combination of a pistol-butt; a detachable knuckle-duster having an opening for each finger, and a rearward extension engaging under and secured to the lower end of the pistol-butt and provided at its lower part with a recess, the uppermost opening being elongated horizontally and forming the

trigger guard, while the remaining openings are arranged in front of and approximately parallel to the pistol butt with the lowermost opening disposed slightly lower than the lower end of the butt; a pivot pin passing through said recess perpendicular to the axis of the butt; and a thrust blade pivoted at its inner end on said pivot-pin and adapted to be moved into alinement with the butt and also to be placed parallel with and flat against the side thereof in which position it may be held flat by means of the thumb and finger ends as the butt and duster are held.

In testimony whereof, I have signed my name to this specification in the presence of two subscribing witnesses.

BÉLA KREITH.
